STEERING WHEEL

Elmer C. Kiekhaefer, Cedarburg, Wis.

Application October 22, 1954, Serial No. 32,783

Term of patent 14 years

(Cl. D14—30)

FIG. 1.

FIG. 2.

FIG. 3

Figure 1 is a plan view of a steering wheel embodying my new design;

Fig. 2 is a side elevation thereof; and

Fig. 3 is a side view at right angles to that of Fig. 2 and having the rim of the wheel broken away so that the contour of the spokes of the wheel can be determined.

I claim:

The ornamental design for a steering wheel, as shown and described.
